UNITED STATES PATENT OFFICE.

STANLEY ANTHONY, OF BOSTON, MASSACHUSETTS.

INDEX.

1,419,194.

Specification of Letters Patent. Patented June 13, 1922.

Application filed August 14, 1916. Serial No. 114,674.

To all whom it may concern:

Be it known that I, STANLEY ANTHONY, a citizen of the United States, residing at Boston, county of Suffolk, State of Massachusetts, have invented an Improvement in Indexes, of which the following description, in connection with the accompanying drawing, is a specification, like characters on the drawing representing like parts.

This invention relates to indexes such as are used in business houses for cataloguing lists of names comprising mailing lists, addresses, telephone numbers, etc., or for cataloguing any other data relative to the business in which the index is used, and among the objects of the invention are to provide an improved index having the capability of containing a large number of names or a large amount of data in a very compact space and in such a way that any index member is readily accessible, to provide an index comprising a plurality of index cards situated in overlapping relation in which each index card can be readily removed from its carrier without removing the carrier from the holder; to provide an improved hinge connection between each card and its carrier; to provide an improved carrier for the cards; to provide an improved card constructed to removably receive a plurality of index elements and provided with a novel protecting cover for protecting said elements, and otherwise to improve indexes of this nature, all as will be more fully hereinafter specified.

In order to give an understanding of the invention, I have illustrated in the drawings some selected embodiments thereof which will now be described, after which the novel features will be pointed out in the appended claims.

In the drawings, Fig. 1 is a perspective view of a construction embodying my improvements;

Fig. 2 is a detail view of the carriers of the cards;

Fig. 3 is a vertical sectional view through a few of the cards and their carriers in assembled relation;

Fig. 4 is a transverse sectional view;

Fig. 5 is a vertical sectional view through one of the cards;

Fig. 6 is a perspective view of the hinge element by which the card is hinged to its carrier;

Fig. 7 is a fragmentary view of the upper

edge of the card showing the manner in which the card is constructed to receive the hinge member;

Fig. 8 is a view showing the manner in which the hinge member is applied to or removed from the card;

Fig. 8^a is a perspective view of a carrier embodying my invention having a different construction than that shown in Fig. 2;

Fig. 9 is an enlarged view of one of the cards;

Fig. 10 is a similar view showing a different form of card;

Fig. 11 is a section on the line 11—11, Fig. 10.

The index herein shown is of that type comprising a plurality of cards carried by a holder and arranged in overlapping relation, said cards being individually removable from the holder and also pivotally mounted therein so that any card can be swung upwardly to uncover and give access to the card directly beneath. The cards are indicated generally at 1 and the holder in 2 in which the cards are sustained at 3.

Each card is pivotally sustained on a carrier 4, and the carriers are retained in position relative to the holder 2 by lips 3 formed on the holder and which form therewith guides in which the ends of the carrier are slidably received.

One feature of my present invention relates to a construction which permits the cards to be readily removed from their carriers without removing the carriers from the holder. The advantage of this is that if it becomes necessary to make any change in the data borne by any card, then the card can be readily removed from its carrier while the carrier is still in the holder, and the presence of the carrier in the holder will hold the other cards properly spaced. The space formerly occupied by the card which has been removed will give an indication as to the proper position in which to insert said card when the change has been made.

The carriers 4 may be made in various ways without departing from the invention. In Figs. 2, 3 and 4 I have shown a carrier 105 made of a length of resilient wire having its ends 5 bent back to form a loop and the extremity 6 of each end constituting a trunnion or pintle on which the card is hinged. These trunnion or pintle portions 6 will preferably be offset slightly from the body of the carrier, as seen

plainly in Fig. 4, so that while the carrier rests against the holder 2, the pintle portions 6 are spaced therefrom. In indexes having this overlapping card feature, it is necessary that the cards should be spaced a certain distance from each other in order that they may be freely operated, and this spacing is herein accomplished by the carriers themselves. The carriers are so made that the portions 5 thereof with the pintles 6 are separated from the main part 4 of the carrier a distance equal to the desired spacing, and hence when the carriers are placed in the holder 2 and rest one on the other, the pintle portions 6 of the adjacent carriers will be separated sufficiently to give the cards 1 the proper spacing.

In order to prevent any possibility of the carriers slipping past each other in the holder, I will preferably make each carrier with the offset portion 7 at each end, these offset portions 7 constituting guard projections that prevent the carriers from slipping by each other. Any carrier with its card thereon can be readily removed from the holder 2 by simply bending the central portion of the carrier outwardly away from the holder, thus withdrawing the ends of the carrier from beneath the lips 3. The card can be readily removed from its carrier by simply bending the card centrally so as to withdraw it from the inner ends of the pintles 6, as will be more fully hereinafter described. The construction is such that the card can be removed from its carrier without removing the carrier from the holder if desired.

In Fig. 8^a I have shown a different form of carrier which, however, embodies the same principle as the carrier shown in Figs. 2, 3 and 4. In said Fig. 8^a the carrier is made from a strip 60 of sheet metal which is preferably resilient and is of a size to be held by the lips 3 of the holder 2. Each strip 60 is of a width corresponding to the spacing desired between adjacent cards, and hence when the carriers are in the holders 2, they will operate to space the cards properly. Each carrier has struck up therefrom a pintle-forming portion 61, each pintle-forming portion having the part 62 which is bent laterally at right angles to the strip 60 and the pintle portion 63 which is bent parallel to the strip 60. The pintle portions 63 are shaped so as to present a cylindrical pintle, and the pintle portions of each carrier are directed toward each other. By this construction the pintles of each carrier are offset from the body of the carrier so that the cards can be readily turned.

In indexes of this type where the individual cards are frequently turned up to give access to the card beneath, it is desirable that the pivotal or hinge connection between the cards and the carriers should be a strong one and one which will not give way after re-

peated use. One feature of my present invention relates to a novel pivotal connection between the card and its carrier which meets these requirements. My improved pivotal connection is formed by a metal hinge member 8 which is detachably secured to the card and which is adapted to be pivotally mounted on the pintle portion 6 of the carrier. Each hinge member 8 is shown as presenting the pintle-receiving portion 9 through which the pintle 6 extends, the two arms or side pieces 10 having at their ends the laterally-extending lips 11 and the central resilient finger 12 which is situated between the side arms 10 and extends slightly beyond the lips 11. This resilient finger 12 is offset from the arms 10 slightly at its inner end, as shown at 13, the offset being substantially equal to the thickness of the card. The card 1 is formed with two slots 14 of a size and properly positioned to receive the lips 11 and is also formed in its upper edge with a notch 15 of a size to receive the offset portion 13 of the resilient arm 12.

When the hinge member is applied to the card, the arms 10 overlie one face of the card with the lips 11 occupying the slots 14, and the offset portion 13 occupies the notch 15, the resilient finger 12 lying on the opposite face of the card from the arms 10 and by its resiliency holding the slots 14 of the card in engagement with the lips 11. The hinge member is thus securely held to the card and because of its construction the card can be repeatedly turned up about the pintles of its carrier without danger of injuring the card or the hinge connection. The hinge member can be readily removed from the card by bending the resilient finger 12 away from the arm 10 sufficiently to permit the slots 14 to be withdrawn from the lips 11, as shown in Fig. 8, after which the hinge member may be readily withdrawn from the card. The hinge member may also be easily applied to the card by opening the finger 12 away from the arms 10 sufficiently to permit the edge of the card to be inserted between said finger and the arm. The fact that the end of the finger 12 extends beyond the arms facilitates the operation of applying the hinge member to the card or removing it therefrom. The hinge member thus presents one portion which overlies one face of the card and has two lips to extend through the apertures therein and another resilient portion which overlies the other face of the card and yieldingly holds the lips in the apertures.

The hinge members 8 will be placed in position on the cards before the cards are attached to the carrier. The operation of connecting a card to its carrier simply involves sliding the pintle-receiving portion 9 of one hinge member over one pintle 6 and then bending the card sufficiently to permit the pintle-receiving portion of the other hinge

member to be slipped over the other pintle. When the card is on the carrier said card is prevented from longitudinal movement relative to the carrier by the engagement of the 5 hinge members with the offset portions 16 of the carriers.

The card can be readily removed from its carrier by bending said card centrally in an outward direction sufficiently to permit one 10 hinge member to be withdrawn from its pintle and then withdrawing the other hinge member from its pintle. These operations of removing the card from its carrier or placing the card on the carrier can be performed 15 equally well whether the carrier is in the holder or is removed from the holder, and one important feature of my invention lies in the capability of removing the cards from their carriers without removing the carriers 20 from the holder. This is quite an advantage, especially where the reason for the removal of the card is simply to make some change in the data thereon, and if it is desired to replace the card in its proper position in the 25 holder after such change is made. Suppose, for instance, it is desired merely to change an address on the card. The card can be removed from its carrier without removing the carrier from the holder, and because 30 the carrier remains in the holder, the relative position of the cards remaining in the holder will be unchanged. There will thus exist a space at the place where the card has been removed, thus indicating the 35 position in which the card is to be placed after the change is made. If it was necessary to remove the carrier with the card, then such removal of the carrier would allow the other carriers to shift their position 40 relative to each other, and the particular place where the removed card belongs would be lost. By means of my invention, however, it is possible to preserve an indication of this place, thus facilitating the re-insertion 45 of the card into the holder after the correction has been made thereon.

So far as the construction above described is concerned, the cards 1 might be designed to receive any desired data. Each card might 50 be devoted to one particular name or one particular subject, or each card might be constructed to receive a plurality of names or subjects. In the construction herein illustrated, each card is constructed to sustain re- 55 movably a plurality of index strips, each strip having a capacity for receiving one name or address or telephone number, etc. With this arrangement, each card might correspond to a letter of the alphabet and it 60 would have on it several names beginning with that letter.

The card construction illustrated is one in which the card has at each end a retaining lip 17 which is adapted to overlie the 65 ends of and hold in place index strips 18 of

paper or similar material. Each strip may be of a size to receive one name and address or telephone number. These index strips are arranged one above the other, as shown in Fig. 9 with the ends thereof slipped under 70 and retained in position by the lips 17. I will preferably provide these retaining lips 17 on each side of the card so that the index strips 18 may be used on both sides of each card. 75

These index strips usually have the data either written or typewritten thereon, and it is desirable to protect the strips from being soiled by the constant handling of the index. I accomplish this herein by securing to each 80 side of the card a protective cover in the form of a sheet 19 of celluloid or some similar transparent but flexible material. I will preferably secure each cover 19 centrally to the card 1 at the top and bottom edges, the 85 ends 20 of the cover being free to be turned up, as shown in Fig. 9, thereby giving access to the individual strips 18. The ends 20 of this protective cover are retained in position underneath the lips 17, and to facilitate the 90 insertion of said ends under the lips, I propose to make the ends 20 rounded somewhat. When the cover is in place, the data on the individual strips 18 can be readily read. If it is desired to remove any of the strips 18 95 or to add new index strips to the card, then one or both ends 20 of the protective cover can be withdrawn from the lips 17 and turned up, as shown in Fig. 9, thereby exposing the index strip 18. The index strip 100 can then be readily removed or inserted and any desired adjustment made relative to the position of the index strips, after which the protective cover may be replaced in position. Where this construction is provided each, 105 card constitutes a holder which is adapted to removably receive a plurality of index strips and by arranging the cards in the holder 2 in the overlapping relation shown, an extremely compact device is provided in 110 which a large number of index strips can be confined in a very small compass.

While the protective cover 19 may be applied to the card in any suitable way I have herein illustrated a construction wherein the protective cover for both sides of the card is made from the same celluloid sheet, the latter being folded around the lower edge of the card and the upper edges of the sheet being secured to the upper end of the card in 115 some suitable way as by eyelets 21. At the lower edge of the card the protective cover is cut from the ends inwardly to the points 22 to allow the ends of the protective cover to be readily turned up. 120

In Fig. 10 I have illustrated a slightly different embodiment of the invention where in each protective cover is made in sections so that it is possible to turn up a portion only thereof at each end. In this embodiment 130

ment the cover is slit inwardly from its outer edges a plurality of times, as shown at 23, thus making the cover sections 24. The advantage of this construction is that when it is desired to remove or adjust any particular index strip it will be necessary to turn up only the section of the protective cover which immediately overlies the particular index strip. In this construction I have shown 10 the central portion of the protective cover as held in position by wires 25 which extend through apertures 26 in the top and bottom edge of the card.

The holders such as shown in Fig. 1 may 15 be used individually or collectively, depending upon the size of the index which it is necessary to use. If said holders are used collectively a plurality of them may be mounted on a standard or support in any 20 suitable way so that anyone of the holders can be brought into accessible position.

I claim:

1. In an index, the combination with a holder having a retaining lip at each edge, 25 of a plurality of resilient card carriers removably retained in position by said lips, an index card carried by each carrier said carrier and card being constructed to permit the removal of the card from the carrier 30 without removing the carrier from the holder, each carrier having at some point between its ends an increased lateral dimension whereby the carriers are prevented from slipping past each other in the holder.

35 2. In an index, the combination with a holder having a retaining lip at each edge, of a plurality of resilient card carriers removably retained in position by said lips, an index card carried by each carrier said 40 carrier and card being adapted to permit the removal of the card from the carrier without removing the carrier from the holder, each carrier having at some point between its ends a lateral guard projection 45 to prevent the carrier next above from being displaced.

3. In an index, the combination with a holder having a retaining lip at each edge, of a plurality of resilient card carriers retained 50 in position by said lips, each carrier having a pair of card-receiving pintles and a card pivotally mounted on the pintles of each carrier and capable of removal therefrom without removing the carrier from the 55 holder, each carrier having a laterally extending guard projection to prevent the carrier next above it from being displaced.

4. In an index, the combination with a holder having a retaining lip at each edge, 60 of a plurality of resilient card carriers retained in position by said lips, each carrier having a pair of card-receiving pintles and a card pivotally mounted on the pintles of each carrier and capable of removal there- 65 from without removing the carrier from the

holder, each carrier having a laterally extending guard projection situated between the pintle and the end of the carrier to support the carrier next above.

5. In an index, the combination with a 70 holder having retaining lips at each edge, of a plurality of card carriers retained in position by said lips and each comprising a length of wire having its ends bent back toward each other to present card-carrying pintles, each wire having intermediate of its ends a laterally-offset guard portion, and a card pivotally mounted on the pintles of each carrier.

6. In an index, the combination with a 80 card having two separated apertures spaced from its edge, of a hinge member presenting a resilient portion to overlie one face of the card and having two separated lips to enter said apertures and also having a resilient 85 portion to overlie the other face of the card and yieldingly hold said lips in said apertures and a carrier to which said hinge member is pivoted.

7. In an index, the combination with a 90 card having adjacent each end, two separated apertures spaced from its top edge, of two hinge members, each presenting a resilient portion to overlie one face of the card and having two separated lips to enter 95 two of said apertures and also having a resilient portion to overlie the other face of the card and yieldingly hold said lips in said apertures, said hinge member having a pintle-receiving portion situated beyond the 100 edge of the card and a carrier on which said pintle-receiving portions are pivotally mounted.

8. In an index, the combination with a 105 card having apertures adjacent its edge, of a hinge member presenting two arms adapted to overlie one face of the card and provided at their ends with lips to enter said apertures, and a resilient finger adapted to overlie the other face of the card and yieldingly 110 hold said lips in said aperture, said hinge member having a pintle-receiving portion, and a carrier on which said pintle-receiving portion is pivotally mounted.

9. In an index, the combination with a 115 card having apertures adjacent its edge, of a hinge member presenting two arms adapted to overlie one face of the card and provided at their ends with lips to enter said apertures, and a resilient finger of greater 120 length than said arms adapted to overlie the other face of the card and yieldingly hold said lips in said aperture, said hinge member having a pintle-receiving portion, and a carrier on which said pintle-receiving portion is pivotally mounted.

10. In an index, the combination with a 125 holder, of a plurality of carriers removably sustained thereby, each formed of wire bent to present two card-carrying pintles, a card 130

having two hinge members removably secured thereto and each provided with a pintle-receiving portion which is pivotally mounted on one of the pintles.

- 5 11. In an index, the combination with a holder, of a carrier removably sustained thereby, and formed of wire bent to present two card-carrying pintles, and a card having two hinge members removably secured 10 thereto and each provided with a pintle-receiving portion which is pivotally mounted on one of the pintles, each hinge member presenting two arms adapted to overlie one face of the card and provided with lips to 15 enter apertures in the card, and a resilient finger to overlie the other face of the card and yieldingly hold said lips in said apertures.

12. In an index, the combination with a body member having retaining lips at its edges, of a plurality of index elements retained in position by said lips, and a protective cover of transparent material secured to the body member centrally thereof, the 25 ends of said cover being free to be turned back to give access to the index elements, said ends being rounded and adapted to be inserted under the lips.

13. In an index, the combination with a body member having retaining lips at its edges on both sides thereof, of a plurality of index elements adapted to be retained in position beneath said lips, and a protective cover of transparent material folded about 35 the lower edge of said body member and secured thereto at the upper edge centrally thereof, the ends of the cover on each side of the body member being free to be turned back thereby affording access to the index 40 elements.

14. In an index, the combination with a body member having retaining lips at its edges on both sides thereof, of a plurality of

index elements adapted to be retained in position beneath said lips, and a protective 45 cover of transparent material folded about the lower edge of said body member and secured thereto at the upper edge centrally thereof, the ends of the cover on each side of the body member being free to be turned 50 back thereby affording access to the index elements, said ends being rounded and constructed to be inserted beneath the lips.

15. In an index, the combination with a body member having retaining lips at its 55 edges, of a plurality of index elements adapted to be retained in position beneath said lips, and a protective cover of transparent material overlying said index elements and secured centrally to the body element, 60 the ends of said protective cover being free and being divided so that any section thereof can be turned back to expose the index elements therebeneath without distorting the other sections. 65

16. The combination with a main frame, of a plurality of overlapping holders detachably mounted therein, each holder comprising a body portion, a transparent sheath portion extending over the major part of the 70 body portion, means for removably confining the edges of the sheath portion and a plurality of index slips removably secured between the sheath and body portion.

17. The combination with a main frame, 75 of a holder mounted therein, said holder comprising a body portion having confining lips at either side thereof, a transparent sheath extending across the face of the body portion and having its free edges detachably 80 seated beneath said lips and a plurality of index slips removably supported between the sheath and body portion.

In testimony whereof, I have signed my name to this specification.

STANLEY ANTHONY.
